PORTABLE POWER TOOL FOR POLISHING OR SANDING OR THE LIKE

Donald Lee, 3633 Strandhill Road,
Shaker Heights, Ohio 44122

Filed Jan. 29, 1968, Ser. No. 10,342

Term of patent 14 years

Int. Cl. D8—02

U.S. Cl. D8—62

Fig. 4

Fig. 5

FIG. 1 is a top plan view of a portable power tool for polishing or sanding or the like;

FIG. 2 is a side elevational view as seen from the top of FIG. 1 showing my new design;

FIG. 3 is a front elevational view as seen from the left-hand side of FIG. 1 showing my new design;

FIG. 4 is a side elevational view as shown from the bottom of FIG. 1 showing my new design; and

FIG. 5 is a rear elevational view as seen from the right-hand side of FIG. 1 showing my new design.

The broken line disclosure in FIG. 1 of the electrical cord and in FIGS. 2, 3, 4 and 5 of the driving pad is for illustrative purposes only.

I claim:

The ornamental design for a portable power tool for polishing or sanding or the like, as shown and described.
